UNITED STATES PATENT OFFICE.

FREDERICK VAN DYKE CRUSER, OF BARBERTON, AND WILLIAM GREEN, OF AKRON, OHIO, ASSIGNEES TO THE DIAMOND MATCH COMPANY, OF CHICAGO, ILLINOIS, A CORPORATION OF ILLINOIS.

MATCH-TESTING MACHINE.

1,122,576.

Specification of Letters Patent. Patented Dec. 29, 1914.

Application filed April 5, 1913. Serial No. 759,102.

To all whom it may concern:

Be it known that we, FREDERICK V. D. CRUSER and WILLIAM GREEN, citizens of the United States, and residents, respectively, 5 of Barberton and Akron, in the county of Summit and State of Ohio, have invented certain new and useful Improvements in Match-Testing Machines, of which the following is a specification.

10 The object of this invention is to provide an apparatus of simple and efficient construction and operation for testing matches in order to determine the frictional ignition sensitiveness or striking efficiency of 15 the composition comprising the heads of the matches.

Our invention, broadly considered, comprehends a structure embodying match-striking and match-holding members which 20 are so coördinated that the head of a specimen match supported by said holder can be subjected to a predetermined co-efficient of friction closely approximating that resulting from the usual manual operation of 25 striking a match.

The invention also comprises a rotatable striking member, and means whereby a specimen can be supported adjacent to, and its head moved into frictional contact with 30 said member.

The invention also comprises various novel features of construction and combinations of parts, all of which will be hereinafter described and claimed.

35 In the drawings Figure 1 is a plan view of an apparatus embodying a good form of our invention, a specimen match being indicated therein. Fig. 2 is a side elevation thereof. Fig. 3 is an end view of the same.

40 Fig. 4 is a detail, enlarged, partly in section of the rear of the upper portion of the match-supporting element. Fig. 5 is an edge view of Fig. 4, the match being shown in section.

45 11 designates a rotary friction member comprising a disk fast on one end of a horizontal shaft 12 having its bearings in standards 13 on an appropriate base-plate 14. On the opposite end of the shaft is a pulley 50 15 which is driven from a suitable source of power. The acting surface of the disk may be faced with frictional paint or other material, as indicated at 16.

17 designates a vertically-disposed lever

which is pivotally mounted in such manner 55 that its upper arm is movable toward and from the acting face of the disk. In the present instance the lever is supported by and between oppositely-disposed pivot studs, comprising screws 18, one of which 60 is borne by an up-projecting flange 19 at the outer edge of the base-plate and the other by a bracket 20 fastened to said flange. The lower arm of the lever depends below the base plate and is provided with a weight 21 65 which may be secured in positions of adjustment longitudinally of the lever by means of a set-screw 22. This weight constitutes a bob which tends to maintain the lever normally in vertical position. The 70 upper arm of the lever extends adjacent to the horizontal diameter of the disk, near the periphery of the latter, and is provided with a spring-clip comprising complementary spring-metal plates 23 bent into channel-form at their inner upper edges to provide gripping jaws by and between which a match splint, (as a), may be clamped with its head adjacent the disk. The lower portions of the plates are fastened to the lever 75 by rivets, or the like. Affixed to one side of the upper arm of the lever is a finger 24, the upper end of which extends into the plane of the match in the grasp of the clip, and serves as a backer for the outer end of 80 the match. This member is preferably provided with a socket 25 to receive and support the heel of the match. The flange 19 is extended below the base-plate 14 and is provided with a series of apertures 26 which 85 are bored at regular intervals apart in an arc described from the axis of oscillation of the lever. These orifices are designed to receive a stop-pin 27 which may be inserted into any one of them, which pin when so inserted extends into the path of the lower arm of the lever and acts as a determinate stop therefor. In the present instance there are ten orifices, numbered consecutively 90 from a point adjacent the lever when it is in vertical position, as indicated in Fig. 2, whereby the pin can be adjusted to graduated limits within a comparatively wide field.

95 The operation is as follows: Power being 105 applied to the drive pulley, the disk is rotated at a predetermined speed; a match is applied to the clip at the upper end of

the lever and thereby firmly held with the head of the match adjacent to, but out of contact with, the acting face of the disk, and the lower arm of the lever is then manually 5 swung to the left, as viewed in Fig. 2, until its movement is limited by the projecting pin 27. The lever is then released, and, by virtue of the energy exerted thereon by the gravitation of the weight, the depending 10 arm of the lever swings sharply toward the right until the head of the match impinges against the opposing rotating surface of the disk; the frictional impact closely approaching that to which a match is subjected in the ordinary manner of manually 15 striking the same. The friction may be nicely varied by initially setting the weight on the arm at a predetermined distance from the axis of the lever and then advancing 20 the stop step-by-step (commencing with the aperture "1") preparatory to each operation of the lever, until the match head shall be ignited by its contact with the striking member. Thereupon the degree of ignition 25 sensitiveness of the head will be indicated.

As a simple and convenient means to remove the ignited match from the clip a spring arm 28 is preferably arranged to extend beneath the match near its head, which 30 arm when depressed and released flies upward against the opposing match and ejects it from the clip. In the present instance this arm comprises the extended end of a coiled spring 29 which is secured to a stud 35 30 fast on a suitably-located bracket piece 31 on the upper arm of the lever 17.

It is to be understood that our invention is not limited to the particular form or construction herein shown and described, as 40 the structure may be variously modified without departure from the spirit of the invention.

We claim—

1. A match-testing machine comprising a 45 supporting frame, a rotatable friction member, a match support adapted to present a match to the face of said member, and adjustable means whereby the said support may be sharply moved with a predetermined 50 force toward the said member so as to pro-

ject the match head against and maintain it in rubbing contact with the opposing face of the member.

2. In a match-testing machine, a rotary striking member, a lever adjacent thereto, actuating means for said lever, a match holder on said lever adapted to present a match to said striking member and an adjustable stop for determining the starting limit of said lever. 55

3. In a match-testing machine, a rotary striking member, an oscillatory lever adjacent thereto, a match holder on one arm of the lever adapted to present a match to said striking member, an adjustable weight 65 on the other arm of the lever, and an adjustable stop for determining the starting limit of said lever. 60

4. A match-testing machine comprising a supporting frame, a shaft therein, means 70 for rotating said shaft, a friction disk on said shaft, a lever mounted to oscillate adjacent said disk, a match holding element on one arm of said lever adapted to present a match to said disk, an adjustable weight 75 on the other arm of the lever, a stationary element provided with a series of spaced orifices adjacent the path of the lever, and a stop adapted to be detachably inserted in any of said orifices in order to determine 80 the starting limit of said lever.

5. In a match-testing machine, a rotary match striking member, a match support mounted for movement toward and from said member, said support having a spring- 85 clip by means of which a match may be clamped with its head pointing toward said member, and adjustable means for said match support whereby a predetermined rubbing impact of the match head and said 90 member can be effected. 90

Signed at Barberton in the county of Summit and State of Ohio this first day of April A. D. 1913.
